CIGARETTE EXTINGUISHING MEANS AND
ASH RECEPTACLE

Arthur John Gaskin, Elwood, Victoria, Australia

Application October 12, 1948, Serial No. 54,146
In Australia December 3, 1947

9 Claims. (Cl. 131—235)

1

This invention relates to smokers' devices and one general object is to provide a receptacle embodying novel means for extinguishing cigarettes and cigars.

A specific object is to provide a smoker's device having a readily penetrable extinguishing pad of finely divided ferro-magnetic material supported magnetically between the poles of a magnet with a free air space below said pad.

Another specific object is to provide a device having a body housing a magnet and incorporating an ash cavity, said body or housing being formed above the bottom of the ash cavity with a slot which extends between the poles of the magnet and in which said pad of ferro-magnetic material may be accommodated.

A further object is to provide a smoker's device adapted to be attached magnetically to a support of ferrous metal.

Yet another object is to provide a device having a magnet which is so arranged as to support the said extinguishing pad and also enable said device to be attached magnetically to a support.

In the ensuing description of exemplary forms of the invention, reference is made to the accompanying drawings, in which:

Figure 1 is a view in sectional side view of a smoker's device incorporating the invention;

Fig. 2 is a view in plan of the device shown in Fig. 1;

Fig. 3 is a view in sectional elevation taken on the line 3—3 of Figure 2;

Fig. 4 is a view half in plan elevation and half in sectional plan of a portion of the housing of the device taken on the line 4—4 of Fig. 3;

Fig. 5 is a view similar to Figure 3 and shows a modification embodying an electromagnet;

Fig. 6 is a view in perspective of one form of ash tray in accordance with the invention;

Fig. 7 is a view in section taken on the line 7—7 of Fig. 6;

Fig. 8 is a view in section taken on the line 8—8 of Fig. 6.

The smoker's device shown in Figures 1 to 4 has a housing comprising an inner portion 10 and an outer portion 10a both moulded from suitable plastic material, the said outer portion being in the form of a horizontally disposed cylindrical shell which is closed at the front and open at the back and which additionally is formed at the top with a relatively large opening 10b which provides access to the interior thereof.

The inner portion 10 of the housing is arranged within the outer portion 10a thereof and 55

2

serves as a partial closure therefor for which purpose the rear end of said inner portion is flat and arcuate and fits neatly within the said outer portion, while the forward end of said inner portion is located by an internal shoulder 10c in the outer portion.

Forwardly of the back, the inner body portion 10 is of hollow U shape in vertical section whereby a longitudinally extending slot 12, of sufficient width to permit a cigarette 16 to pass, is formed between the spaced upper portions thereof. This slot is in register with the opening 10b in the top of the outer portion of the housing and the sides of the said slot are defined by spaced inner walls 10³ which merge together at their lower ends at 10⁴ to define the bottom of the slot.

This slot 12 is open at its forward end and the bottom 10⁴ thereof inclines forwardly and downwardly whereby ash which falls thereonto will be directed into an ash compartment 11 in the forward part of the outer portion 10a of the housing.

The hollow interior of the inner housing portion 10 is also U-shaped in vertical section and the U-shaped cavity is closed at the front but extends to the back thereof, so that a permanent magnet 13 of incomplete circular or so-called "horseshoe" shape may be inserted thereinto and secured therewithin as by means of a suitable cement. The spaced arms 13¹ of the magnet thus extend upwardly within corresponding spaced hollow portions 10⁵ of the housing 10 whereby the pole portions formed by the upper ends 13² of the magnet arms are disposed outwardly of, and substantially in contact with, the upper ends of the respective inner walls 10³ which define the opposite sides of the slot 12.

Accordingly, the field of the magnet extends through the said walls 10³ and across the upper portion of the slot 12.

After the magnet is fixed in position, the open back of the housing is closed by a thin flat disc 20 which is suitably secured in position and the outer surface of this disc is covered with frictional material 21, such as rubber, to resist sliding movements when the receptacle is attached to a vertical support as hereafter explained.

A pad 15 of finely divided ferro-magnetic material is arranged horizontally within the slot 12 between the pole portions 13² of the magnet 13 and is retained in such position solely by the magnetic field, such pad being preferably formed of magnetic oxide of iron, ground to a substantially impalpable powder.

The particles of the ferro-magnetic material

form spicule like aggregations which extend generally in the direction of the magnetic field across the slot and the pad formed thereby is soft and yieldable in character so that the lighted end of a cigarette 16 may readily penetrate the same.

The cigarette when so inserted is quickly extinguished partly by lack of sufficient air to sustain combustion and partly by thermal conduction.

It is important to observe that as shown in Figures 1 and 3 the pad 15 is disposed some distance above the sloping bottom 10⁴ of the slot 12 whereby a free air space is provided therebetween so that ash is free to fall from the pad and is then directed into the compartment 11.

Moreover, the extinguished cigarette may be left supported in the pad 15 and when it is subsequently withdrawn the cavity formed thereby in the said pad is partly refilled, by the consequent redistribution of the ferro-magnetic particles within the magnetic field.

Ash or other non-magnetic material which is deposited on or within the pad may be removed to a sufficient extent by inverting the device and shaking or tapping same.

The said pad may be formed by "pouring" the powdered ferro-magnetic material into the slot 12 between the poles of the magnet but the same is preferably supplied as a paper wrapped refill which may be inserted in the required position after which the paper wrapping may be burnt off.

As the rear portions of the free upper ends 13² of the magnet are disposed in contact with the closure disc 20, the magnetic field also extends through the space immediately behind the device and the latter may thus be readily retained by magnetic attraction to a steel support 18 and it will be evident that the rubber covering 21 tends to prevent the device from slipping downwardly when the same is supported in this way.

In addition, the lower portion of the body portion 10^a is preferably formed with integral projections 10^d which enable the device to be supported in an upright position on a table or the like.

While it is preferred to provide a single magnet for forming the pad 15 and for enabling the receptacle to be magnetically attached to a support, it will be obvious that if desired separate magnets may be employed for these purposes. Also, when it is desired to provide a single receptacle with a plurality of pads 15, the device may include a plurality of magnets of suitable shapes arranged in the required positions.

It will be evident that if desired an electro-magnet may be used in lieu of the permanent magnet 13 and Figure 5 is a view similar to Figure 3 showing by way of example, the substitution of an electro-magnet 24 provided with winding 25 to which current may be supplied from any suitable source by conductors 26.

The ash tray shown in Figures 6 and 7 comprises a housing generally designated 110 in the form of a thin shell moulded from suitable plastic material, such shell being hollow on its underside and comprising a circular base with an upstanding hollow rim 110¹ and an integral upstanding hollow central projection 110² arranged on opposite sides of and defining an ash and match holding annular groove 111.

The upper portion of the central projection 110² is shaped to form a relatively deep di-

ametrically disposed slot 112 of sufficient width to pass a cigarette and the sides of which are formed by spaced opposed portions of the projection. The lower portion of this slot is parallel 5 sided, while the upper portions of said sides diverge upwardly as best shown in Figure 7. The slope downwardly and merge into the corresponding portions of the annular groove as shown in 10 Figure 8.

A permanent magnet 113 of incomplete circular or so-called "horseshoe" shape is arranged within the hollow central projection 110² of the housing 110 with the opposed arms 113 directed vertically 15 upwards whereby its free upper ends which form the pole portions thereof are disposed on opposite sides of the slot 112 whereby the field of the magnet extends transversely across said slot between the poles of the magnet. Thus the 20 pole portions of the magnet are located within the spaced hollow portions of the housing on opposite sides of the slot 112.

The magnet is retained in position within the shell in any convenient manner such as by embedding same in a body 114 of suitable material 25 such as plaster with which the hollow shell 110 is filled.

Preferably, the sides and bottom of the diametrical slot 112 are lined by inserting within 30 said slot an arcuate member 130 and having a U-shaped section and formed of thin resilient metal which is frictionally retained in position and which may readily be removed for cleaning.

A pad 115 of finely divided ferro-magnetic material is arranged horizontally within the slot 112 between the pole portions of the magnet 113 and is retained in such position by the magnetic field, such pad being preferably formed of magnetic oxide of iron, ground to a substantially im- 40 palpable powder.

The particles of the ferro-magnetic material form spicule like aggregations which extend generally in the direction of the magnetic field across the slot and provided the constituent particles are sufficiently fine, the pad formed thereby is soft and yieldable in character so that the lighted end of a cigarette 16 may readily penetrate the same.

The cigarette when so inserted is quickly extinguished partly by lack of sufficient air to sustain combustion and partly by thermal conduction.

It will be observed from Figure 8 that the pad 115 is disposed some distance above the bottom of the slot 112 whereby a free air space is provided therebetween so that ash is free to fall from the pad onto the sloping bottom of the slot and by which it is directed into the annular groove 111.

Moreover, the extinguished cigarette may be left supported in the pad 115 and when same is subsequently withdrawn the cavity formed thereby in the said pad is partly refilled, by the consequent redistribution of the ferro-magnetic particles within the magnetic field.

Ash or other non-magnetic material which is deposited on or within the pad may be removed to a sufficient extent by inverting the device and shaking or tapping same.

The said pad may be formed by "pouring" the powdered ferro-magnetic material into the slot 112 between the poles of the magnet but same is preferably supplied as a paper wrapped refill which may be inserted in the required position after which the paper wrapping may be burnt off.

Although the magnetic field is of maximum intensity in the space between the poles of the mag-

net, it extends also through the space immediately surrounding the upper end of the central projection 110² so that a suitably shaped steel support 117 for a cigarette or cigar may be retained thereto by magnetic attraction. It is to be noted that this support 117 is disposed inwardly of the outer rim of the shell 110, so that if a cigarette should fall therefrom, it will be received within the annular groove 111, thus reducing the risk of damage to tables and covering thereof.

I claim:

1. A device for use in extinguishing cigarettes and the like comprising a magnet, a support therefor, said magnet having spaced adjacent poles with a free accessible space therebetween of sufficient width to permit a cigarette to pass, a readily penetrable extinguishing pad of finely divided ferro-magnetic material magnetically supported solely by the magnetic field within said space between the said poles and guiding means constituting part of said support for guiding particles of ferro-magnetic material to the zone of the magnetic field.

2. A smoker's device having a housing formed with an ash receiving cavity, magnet means arranged within and completely enclosed by said housing, said magnet means incorporating an adjacent pair of opposite pole portions with an exposed free space therebetween of sufficient width to permit a cigarette to pass and a readily penetrable extinguishing pad of finely divided ferro-magnetic material magnetically supported between said pole portions, said pad being disposed above and spaced from the bottom of said cavity whereby there is a free air space below said pad.

3. In a smoker's device, a housing of plastic material formed with an ash retaining cavity and magnet means carried in said housing and having a pair of spaced and substantially horizontally opposed pole portions disposed above the bottom of said cavity, said housing having a spaced pair of substantially parallel portions extending between and at least partly above said magnet pole portions and defining the opposite sides of an intervening slot of sufficient width to permit a cigarette to pass, whereby a readily penetrable pad of finely divided ferro-magnetic material may be magnetically supported within said slot in spaced relation to the bottom of the slot.

4. In a smoker's device, a housing having a substantially flat back and formed with an ash retaining cavity disposed forwardly of said back, a magnet arranged within said housing and having spaced pole portions of opposite polarity disposed above the bottom of said cavity and adjacent the back thereof, whereby the field of said magnet will extend into the space behind said back of the housing and enable the latter to be magnetically attached to a support of ferrous metal, said housing having spaced hollow wall portions within which said magnet pole portions are located and which define therebetween an exposed slot of sufficient width to permit a cigarette to pass, whereby a readily penetrable pad of finely divided ferro-magnetic material may be magnetically supported within said slot in spaced relation to the bottom of the slot.

5. In a smoker's device, a hollow housing having a substantially flat back, said housing being formed with an ash retaining cavity which is open at the top, a "horseshoe" magnet arranged substantially vertically within the rear portion of

the housing having opposed arms disposed adjacent the back thereof and with the free ends of said arms uppermost, said housing including spaced hollow portions of non-magnetic material extending forwardly from the back thereof and enclosing the respective free ends of the magnet, said spaced portions defining opposite sides of a transverse slot which extends between the said free ends of the magnet and terminates in advance thereof but rearwardly of the front wall of the housing whereby a readily penetrable pad of finely divided ferro-magnetic material may be magnetically supported within said slot in spaced relation to the bottom of the slot and between said free ends of the magnet and wherein said magnet produces an external magnetic field in the space behind the housing whereby the latter may be magnetically attached to a support of ferrous metal, said housing also having a forwardly and downwardly extending ash collecting and diverting surface defining the bottom of said transverse slot, the forward end of said slot being open and communicating with the cavity in the housing in advance of the magnet, said slot being of sufficient width to permit a cigarette to pass.

6. In a smoker's device, a housing formed with an ash retaining cavity, said housing having spaced opposed portions extending substantially above the level of the bottom of the cavity and defining the sides of an intervening slot of sufficient width to permit a cigarette to pass, and a magnet fixed completely within said housing, said magnet having an opposed pair of opposite pole portions located outwardly of and adjacent to said opposed portions of the housing and substantially above the bottom of said cavity, so that the field of the magnet extends through said opposed portions of the housing and across said slot whereby a readily penetrable continuous pad of finely divided ferro-magnetic material may be magnetically supported within the slot with its lower surface disposed above and spaced from the bottom of said cavity.

7. A smoker's device comprising a housing formed with an ash retaining cavity, said housing having spaced opposed portions located substantially above the level of the bottom of the cavity, and forming the sides of an intervening substantially horizontal slot which is open at the top and which is of sufficient width to permit a cigarette to pass, a magnet fixed completely within the housing, said magnet having an opposed pair of opposite pole portions located outwardly of and adjacent to said opposed portions of the housing and inwardly from one end at least of the slot therebetween, a readily penetrable pad of finely divided ferro-magnetic material magnetically supported within and extending continuously across the slot between said pole portions of the magnet and means forming below and spaced from the bottom of said pad an ash diverting surface located above the level and at one side of the bottom of the cavity and adapted to direct ashes thereinto.

8. In a smoker's device, a housing formed with an ash retaining cavity, a magnet secured to said housing and having spaced pole portions disposed substantially in horizontal alignment above the bottom of the cavity, said housing having spaced portions substantially enclosing said pole portions of the magnet and extending upwardly and laterally beyond said pole portions of the magnet and defining opposite sides of an intervening exposed slot of sufficient width to permit a cigarette to pass whereby a readily penetrable pad of finely

divided ferro-magnetic material may be magnetically supported within said slot between said pole portions of the magnet in spaced relation to the bottom of the slot.

9. In a smoker's device, a hollow housing formed of molded plastic material and having a substantially flat back, the forward portion of said housing forming an ash retaining cavity which is open at the top, said housing also having spaced portions extending forwardly from the upper portion of the back and terminating rearwardly of the forward end of the housing, said spaced portions of the housing defining the sides of an intervening slot of sufficient width to permit a cigarette to pass, a "horseshoe" magnet 15 fixed within the rear portion of the housing with the arms thereof extending upwardly and with the free upper ends of said arms arranged at the opposite sides of said slot and outwardly of and close to the respective sides thereof whereby the 20 field of the magnet extends transversely across the slot and through said spaced portions of the housing and also extends into the space behind the back thereof, said housing also having a portion which forms a bottom for said slot and which 25 extends forwardly and downwardly to direct ash

into said cavity therein, said slot being of sufficient depth to enable a continuous readily penetrable pad of finely divided ferro-magnetic material to be magnetically supported within the slot and spaced above the bottom thereof.
